GEORGE F. ROSE, OF NEW YORK, N. Y.

TYPE-WRITER ESCAPEMENT.

1,195,504.

Specification of Letters Patent. Patented Aug. 22, 1916.

Application filed November 7, 1912. Serial No. 729,930.

To all whom it may concern:

Be it known that I, GEORGE F. ROSE, a citizen of the United States, residing in the city of New York, borough of Manhattan, 5 county and State of New York, have invented a certain new and useful Type-Writer Escapement, of which the following is a specification.

This invention is an escapement for type-writers, the object being to produce a simple and efficient means for controlling the step-by-step movement of the platen carriage, the latter being impelled in one direction by a spring.

15 The salient feature of the device is a toothed escapement wheel capable of vibratory and rotary movement.

In a practical embodiment of the invention, the escapement wheel is fitted on a 20 square or polygonal part of a shaft, the latter being journaled in a stationary part of the typewriter and said shaft being provided with a gear which meshes with a rack on the platen carriage. With the vibratory escapement wheel coöperate two dogs, one fixed and the other movable, said dogs being in 25 the path of the teeth on said wheel. The fixed dog is on a bracket or other device positioned on the stationary part of the 30 machine so as to engage with a tooth of the escapement wheel when the latter occupies a lowered position to hold the carriage at rest. The other dog is on a vibratory member which is operated to lift the escapement 35 wheel free from the fixed dog, after which disengagement the carriage spring impels the carriage the distance of one step and the escapement wheel turns for a distance of one tooth, the intermittent motion of the escapement wheel being controlled by the tooth 40 coming into contact with the dog on the vibratory member. Said member is preferably in the form of a bell crank and is operated from the universal bar of the typewriter, said member and the dog thereon 45 serving in a twofold capacity, first, as means for giving the vibratory sidewise movement to the escapement wheel and, second, as a stop to arrest the rotation of the escapement wheel under the energy of the carriage 50 spring.

Other features of the invention, and the advantages thereof, will appear in the course of the following detailed description taken 55 in connection with the drawings.

In the accompanying drawings, I have

illustrated one practical embodiment of the invention, but the construction shown therein is to be understood as illustrative, only, and not as defining the limits of the invention.

Figure 1 is a view in front elevation, partly in section, of a typewriter machine embodying the escapement mechanism of the present invention, the plane of the section being indicated by the dotted line 1—1 of Fig. 2, and certain parts, such as the key action, being omitted. Fig. 2 is a vertical cross section on the line 2—2 of Fig. 1. Fig. 3 is a plan view illustrating a part of the carriage guide and a spring drum with the carriage strap, said view illustrating some of the operating parts of the escapement in full lines and in dotted lines. Fig. 4 is a longitudinal section on the line 4—4 of Fig. 3. Fig. 5 is a cross section on the line 5—5 of Fig. 3, certain of the parts including the pinion being shown in elevation. Fig. 6 is a detail section on the line 6—6 of Fig. 5, illustrating the escapement lever and escapement wheel in raised positions for the purpose of permitting the escapement wheel to clear the fixed dog on a stationary part of the carriage guide, the pinion and certain of the parts being shown in elevation.

A designates a typewriter frame, B a type bar, C C certain finger levers, and D a universal bar supporting the universal levers d and universal rod d'. These parts may be of the usual or any preferred construction. At the rear part of said frame A is a plate a in front of which is an intermediate plate a', and through a slot a² in this intermediate plate extends the rear part of universal lever d. The universal bar actuates a bell crank lever E, shown in dotted lines in Fig. 1, said lever being fulcrumed at e' so that one arm of the lever will extend across universal lever d, whereby the movement of lever d imparts movement to bell crank lever E.

At the upper rear part of frame A is a horizontal plate F which forms the guide for platen carriage G. As shown more particularly in Fig. 2, the carriage guide F is provided at its respective sides with longitudinal flanges f, and the plate forming the carriage bed G is shown as having depending flanges g, the latter fitting within the upstanding flanges f, whereby the carriage bed is fitted slidably to guide F. This carriage bed is provided at its respective ends

with upstanding members g' which support the cylinder platen G' , but obviously the carriage should be equipped with devices usual in the art for retaining, feeding and guiding the paper. To the under side of the plate forming the carriage bed G is rigidly secured a bar H provided with a series of teeth h , said toothed bar forming a rack which extends longitudinally of the carriage 10 for a suitable part of its length so as to be movable with said carriage. With said rack H meshes a gear I , the rack and the gear being positioned in the space between the plates forming carriage guide F and carriage bed G , see Fig. 2. The gear I is secured rigidly to the upper part of a short vertical shaft J , the latter being journaled in a suitable way in a bearing provided in the plate forming carriage guide F , see Figs. 5 and 6. This shaft is free to rotate in its bearings, but it is retained by any suitable means against endwise movement. The lower part of the shaft is journaled in a suitable bearing provided in a bracket K , 20 the latter being positioned below the carriage guide F and having its respective ends k secured rigidly to said guide F , whereby the part of the bracket intermediate the ends k is spaced with respect to the guide F so as to accommodate the escapement wheel L . The shaft J is provided intermediate its bearings in bracket K and guide F with a square or polygonal part j , the latter passing loosely through a correspondingly shaped 30 square or polygonal opening in escapement wheel L , whereby the escapement wheel is loosely fitted on the square part of the shaft so that said escapement wheel is free to vibrate or oscillate with respect to the shaft, 40 and, at the same time said escapement wheel cannot turn idly on the shaft, the result of which is that the escapement wheel will always turn with the shaft but at the same time is capable of the limited independent 45 sidewise movement relative thereto. The escapement wheel is shown in Fig. 3 as having a series of long ratchet-shaped teeth l , and in the normal position of the parts composing the escapement one tooth l of the 50 wheel is adapted for engagement with the fixed one of the two dogs employed in the escapement mechanism, said fixed dog being indicated at M . The fixed dog is attached to, or forms a part of, bracket K which depends from the carriage guide, and when the carriage is at rest the escapement wheel L is pressed by a spring into a substantially horizontal position so that one tooth l of said escapement wheel will be in contact with fixed dog M , the latter co-operating with the escapement wheel and the shaft in restraining the platen carriage from movement under the energy of the carriage spring. 60 As is usual in the art, the carriage spring

N , shown in dotted lines in Fig. 4, is housed or contained within a spring drum n , around which passes a strap N' , said drum n working in a slot n' provided in carriage guide F . The carriage strap N' extends between the bed and guide of the carriage, as shown in Fig. 4, and at one end this strap is provided with a coupling N^2 by which the strap is attached to the carriage in such a manner that the spring will impart movement to the carriage in one direction but this movement is controlled by the operation of the escapement which in turn is controlled and operated by the universal bar associated with the type lever. 70

Vibratory movement is imparted to the escapement wheel by the operation of an escapement lever O , the latter being preferably in the form of a bell crank and fulcrumed at its knee to bracket K by a suitable pin, screw, or other device o . Said escapement lever is arranged for one arm to occupy a horizontal position alongside of escapement wheel L , and for its other arm to depend from the bracket. To the depending arm is connected one end of a rod P , the other end of which is connected to the upstanding arm of bell crank E , see Fig. 1. The connection between rod P and escapement lever O may be effected by any suitable means, but, as shown, the rod is adapted to pass loosely through an aperture in the depending arm of the bell crank O , said rod having a stop p adapted to abut the bell crank. The escapement lever occupies such relation to the escapement wheel that one or more of the long teeth l extend across said escapement lever. 90

Q designates a movable dog which forms a part of, or is attached to, the horizontal arm of the escapement lever. As shown in Fig. 5, the movable dog is in the form of a lug extending upwardly from the top edge of the escapement lever, said dog being in the path of a tooth l on the escapement 105 wheel. When movement is imparted to the escapement lever by the operation of bell crank E and the universal lever, said escapement lever is lifted to the position indicated in full lines in Fig. 6, thus imparting 110 a sidewise movement to the escapement wheel and lifting one tooth thereof from engagement with the fixed dog M , whereupon the pull of the carriage spring, acting through rack H , gear I and shaft J , will turn the escapement wheel for a short distance or until the tooth on said wheel engages with movable dog Q , thereby arresting the further movement of the carriage and the further movement of the escapement wheel. The spring R acts on the escapement wheel to press it back to normal horizontal position and return the escapement lever likewise to its normal position, 120 at which time another tooth l on the escapement wheel will engage with movable dog Q . 125

- ment wheel is brought into engagement with the fixed dog M, thus arresting the movement of the carriage until another key lever is operated. The spring R is shown in Fig. 5 1 as extending longitudinally within the bracket K, said spring having a bent portion intermediate its ends arranged to contact with the escapement wheel L.
- The operation of the escapement mechanism will be understood from the foregoing description. The carriage is restrained from movement under the energy of the spring by a tooth l of the escapement wheel engaging with the dog M. When a finger lever 10 or the space bar is operated movement is imparted to lever E, rod P and escapement lever O, for the purpose of lifting the escapement wheel against the energy of spring R, which movement of the escapement wheel 15 on the polygonal part of shaft J lifts a tooth of said wheel by the dog M, whereupon the pull of the spring on the carriage turns the gear I and shaft J until the tooth of the escapement wheel comes into abutting engagement with movable dog Q, thus arresting 20 the movement of the carriage. The spring R acts to depress the escapement wheel and the escapement lever with the result that another tooth on the escapement wheel comes 25 into contact with fixed dog M, thereby restoring the parts to normal position for a subsequent operation of the escapement mechanism.
- Having thus fully described the invention, what I claim as new, and desire to secure by Letters Patent is:
1. In a typewriter escapement, the combination of a rotatable wheel, fixed and movable dogs in co-operative relation thereto, and means for imparting movement to said wheel, said wheel being mounted for vibratory and tilttable movement relative to said fixed dog.
  2. In a typewriter escapement, the combination with a platen carriage, of a shaft operatively connected with said platen carriage, an escapement wheel rotatable with said shaft and free to vibrate independently thereof, fixed and movable dogs, and means for imparting vibratory movement to said escapement wheel.
  3. In a typewriter escapement, the combination with a platen carriage, of a shaft operatively connected with said platen carriage, said shaft being square for a part of its length, an escapement wheel fitted on said square part of the shaft for rotation therewith, means for moving the escapement wheel sidewise relative to the shaft, and dogs 55 co-operating with said escapement wheel.
  4. In a typewriter escapement, the combination with a carriage, and a shaft co-operating therewith, of an escapement wheel for controlling the rotative movement of said shaft, a fixed dog in the path of said escapement wheel, a movable dog positioned to impart sidewise movement to the escapement wheel and operating to arrest said wheel when it is rotated a predetermined distance, and means for operating said movable dog.
  5. In a typewriter escapement, the combination with a carriage-controlling shaft and a fixed dog, of an escapement wheel for controlling the rotative movement of said shaft, and a movable dog operable to shift said escapement wheel so as to disengage said wheel from the fixed dog, said movable dog being positioned for engagement with said escapement wheel when the latter is turned a predetermined distance.
  6. In a typewriter escapement, the combination with a carriage-controlling shaft and a fixed dog, of an escapement wheel co-operating with said shaft and normally contacting with said fixed dog, a movable dog, and means for operating the movable dog to shift said escapement wheel to a tilted position relatively to the shaft whereby said escapement wheel is disengaged from the fixed dog and the movable dog is positioned for engagement by said escapement wheel.
  7. In a typewriter escapement, the combination with a shaft, and a fixed dog, of a toothed wheel rotatable with the shaft and tilttable thereon, a movable member for imparting tilting movement to said wheel, and a dog on said movable member in the path of a tooth on said wheel.
  8. In a typewriter escapement, the combination with a fixed dog, of a rotatable and tilttable toothed wheel, and an escapement lever provided with a dog, said lever co-operating with the wheel to impart tilttable movement thereto.
  9. The combination of a polygonal shaft, a fixed dog, a toothed wheel positioned on the shaft for tilttable movement relative thereto, an escapement lever for imparting tilttable movement to said wheel, and a movable dog.
  10. In a typewriter escapement, the combination of a shaft, a toothed wheel loose thereon, a fixed dog, a lever co-operating with said wheel for imparting tilttable movement thereto, a dog movable with said lever, and a spring acting on the toothed wheel.
- In testimony whereof I have signed my name to this specification in the presence of two subscribing witnesses.
